COLLAR

Ludwig Bihaly, London, England, assignor to
Trubenizing Process Corporation, New York,
N. Y., a corporation of New York

Application November 23, 1937, Serial No. 176,052

7 Claims. (Cl. 2—131)

This invention relates to a collar or the like, and more particularly to a collar of the fold-over type comprising a collar top portion and a band portion.

5 It is well known that the points or corners of such a collar often have a tendency to curl in wear.

The principal object of my invention is to provide a collar with self-contained means for 10 counteracting this objectionable curling tendency.

Other objects are to accomplish this result in a simple and inexpensive manner, and in such a way as not to interfere with the usual manufacturing technique, or with the launderability 15 of the collar.

Broadly speaking, my invention comprises the application to the collar top of a fabric part having a greater shrinkage than the other fabric 20 parts thereof, and so located that after the collar top is wetted or moistened the differential shrinkage will cause its points to curl inwardly, and thus counteract their normal tendency to curl outwardly in wear.

25 The invention may be applied to a collar of either the shirt-attached or the separate type. It is particularly applicable to a so-called "fused" collar of semi-soft or semi-stiff finish, wherein the plies are adhesively united. Such collars have some resistance to compression in the plane 30 of the collar, which resistance to compression is greatest at the seamed-in edges. It may be used effectively in other collars of such structure as to have an appreciable resistance to compression in the plane of the collar top, either throughout the length of the collar, or in the vicinity of its points only. Such compressive resistance is necessary as otherwise the differential shrinkage would merely result in puckering the collar. The 35 invention may even be applied to a collar of the soft fold type which normally does not have any appreciable resistance to compression. However, in such case, the points should be stretched during laundering to avoid puckering the ends, and the collar should be starched to provide the 40 necessary compressive resistance.

In carrying out my invention I prefer to employ tapes or fabric strips having the desired shrinkage characteristic, and to locate the tapes 45 in the seamed end edges of the collar top. The tapes may, however, be placed in other positions at or in the vicinity of the ends. In each instance the tapes should be so positioned in relation to the collar top that the differential shrinkage will 50 tend to curl the points inwardly.

A preferred embodiment of the invention is illustrated in the accompanying drawing, in which:

Figure 1 is a view of a collar of the fold-over type laid out flat;

Fig. 2 is a view of one end of the bottom ply 5 of the collar top with a piece of tape stitched thereto; and

Fig. 3 is a section of the collar top taken on the line 3—3 of Figure 1.

Referring to the drawing, 11 indicates the collar top generally, and 12 the collar band. The collar may be either of the attached or the detached type, and may be made of one or more fabric plies.

15 The collar top as shown is composed of three plies, namely, a bottom ply 13 and a top ply 14, of suitable material, and an inner ply 15 of lining material. The three plies are stitched together by stitches 16, and then turned in the 20 usual manner to form inturned edges, and further secured by stitches 17 along said edges. The plies may be adhesively united in any known manner.

18 is a piece of tape of about three-sixteenths 25 inch width having a substantially greater shrinkage in the direction of its length than the normal transverse shrinkage of the fabric plies in the completed collar. A piece of such tape may be secured at or near each of the two end edges 30 of the collar top.

A convenient way of manufacturing the collar is to stitch the tape 18 to one surface of the bottom ply 13, after the ply has been cut to shape and before it has been assembled in the 35 collar, by one or more rows of stitches 19, as seen in Fig. 2. The tapes are preferably positioned parallel to the end edges 20 of said ply and so located that when the three plies 13, 14 and 15 are stitched and turned, the tapes will 40 fall within the seamed end edges A as shown in Figs. 1 and 3.

While I prefer to apply the tapes 18 in the position described, it will be understood that the tapes may be in relative positions other than shown. For instance, the tapes may lie between the inturned edges of the top ply 14 and the bottom ply 13, and in that event, the tapes may be sewn either to the top ply 14 or the bottom ply 13; or I may position the tape so that it appears 50 on the external surface of the bottom ply 13 along the end edge of the collar. Furthermore, it is not necessary that the tapes shall lie in the seamed end edges as they may lie in the seamed longitudinal edge B or elsewhere in the neighbor- 55

hood of the points, or tapes may be used both in the end edges and the longitudinal edge. It is essential that the tapes be so positioned that their lengthwise shrinkage will tend to curl the 5 points inwardly.

I have found that when the plies of the collar are made of preshrunk fabrics, the use of tape strips having a lengthwise shrinkage of four to five per cent gives good results.

10 It will be understood that the shrinkage characteristics of the materials here mentioned are their shrinkage characteristics in the dry state as used by the manufacturer in fabricating the collars. The desired differential shrinkage may 15 conveniently be obtained by using preshrunk fabrics for the collar top and by using a tape which has been finished to give the desired shrinkage characteristics, for example, by stretching the tape when it is being finished. The effect of the 20 differential shrinkage is obtained after the collar has been manufactured by the simple expedient of wetting it with water. Even the insensible perspiration of the body may serve to bring out the differential shrinkage characteristics sufficiently to cause the desired inward curling tendency of the points.

The differential shrinkage between the fabric plies on the one hand and the tapes on the other results in the application of a force that tends 30 to curl the points inwardly and thus counteracts their normal tendency to curl outwardly in wear.

The tendency of the tapes to curl the points inwardly will endure through repeated washings of the collar and will be enhanced if the points 35 are stretched after each washing and before they are ironed.

In using the term "points" in the claims, it is to be understood that they need not necessarily be sharp points but that the points or ends of 40 the collar top may be rounded or otherwise shaped.

What I claim is:

1. In a collar, a collar top comprising a lining 45 ply and face plies adhesively united, a strip of fabric secured to each end of the collar top below the lining ply, said fabric strips extending substantially transversely to the length of the collar and having a substantially greater shrinkage in that direction than the corresponding shrinkage of the plies.

50 2. In a collar, a collar top comprising a plurality of plies adhesively united, a strip of fabric

secured to the bottom ply at each end of the collar, said fabric strips extending substantially transversely to the length of the collar and having a substantially greater shrinkage in that direction than the corresponding shrinkage of the plies. 5

3. In a collar, a collar top comprising a plurality of plies adhesively united, and having inturned edges, a strip of fabric secured to one of the plies within the inturned end edge at 10 each end of the collar, said fabric strips having a substantially greater shrinkage transversely of the collar than the shrinkage of the plies in the same direction.

4. In a collar, a collar top comprising a plurality of plies adhesively united and having inturned edges, a strip of fabric secured to the bottom ply within the inturned end edge at each end of the collar, said fabric strips having a substantially greater shrinkage transversely of the 20 collar than the shrinkage of the plies in the same direction. 15

5. In a collar of the character described, a fabric collar top having points, fabric strips secured to the collar cooperating with the collar top near the points thereof, said strips having greater effective shrinkage in their longitudinal direction than the fabric of the said collar top whereby differential shrinkage between the fabric of the collar top and the fabric strips will bias 25 the points inwardly. 30

6. In a collar of the character described, a fabric collar top having points, fabric strips secured to the collar cooperating with the collar top near the points thereof and arranged transversely of the collar, said strips having greater effective shrinkage in their longitudinal direction than the fabric of the said collar top whereby differential shrinkage between the fabric of the collar top and the fabric strips will bias 35 the points inwardly. 40

7. In a collar of the character described, a multi-ply collar top having inturned edges and points, fabric strips having greater shrinkage in a given direction than the corresponding shrinkage of the plies in the same direction, said strips being secured within the inturned edges of the collar top near the points thereof whereby differential shrinkage between the strips and plies will bias the points inwardly. 45
